UNITED STATES PATENT OFFICE.

DANIEL W. KNEISLY, OF JOHNSVILLE, OHIO.

BUGGY-BOOT FASTENER.

SPECIFICATION forming part of Letters Patent No. 630,898, dated August 15, 1899.

Application filed January 7, 1899. Serial No. 701,514. (No model.)

To all whom it may concern:

Be it known that I, DANIEL W. KNEISLY, a citizen of the United States, residing at Johnsville, in the county of Montgomery and State 5 of Ohio, have invented certain new and useful Improvements in Buggy-Boot Fasteners; and I do hereby declare that the following is a full, clear, and exact description of the invention, which will enable others skilled in 10 the art to which it appertains to make and use the same, reference being had to the accompanying drawings, and to the letters of reference marked thereon, which form a part of this specification.

15 My invention relates to improvements in buggy-boot fasteners.

The object of the said invention is to provide a simple and inexpensive fastener that is easily applied to a vehicle and that will 20 hold the buggy-boot firm and prevent any rattling. The invention therefore fulfils the functions of a simple and ready fastening device that may be applied to a buggy without marring in the least the appearance of 25 the buggy and the further function of holding the boot firmly, so that the jolting of the buggy will have no effect on the boot.

To the above ends the invention consists of a double-incline bar or piece rigidly or im- 30 movably attached to the rear end of the body of the buggy and a spring attached to the inner side of the buggy-boot and having two engaging surfaces at its lower end, one adapted to engage with the upper part of the 35 incline, whereby said spring is pressed inwardly, and the other surface adapted to engage with the lower part of the incline, whereby said spring is maintained in firm engagement to hold the boot closed, as hereinafter 40 more fully described.

In the accompanying drawings, Figure 1 is a longitudinal mid-sectional view of the rear end of a buggy, showing my improved boot-fastener attached. Fig. 2 is a similar view 45 showing the contact of the spring with the upper part of the incline-bar as the boot is being pressed to a closed position. Fig. 3 is an elevation of a portion of the inner side of the rear end of a buggy-body, showing the 50 buggy-boot in section and the fastener in position. Fig. 4 are views showing modified

form of spring. Fig. 5 is a view of the spring loop or catch.

The buggy-boot *a* is constructed of any suitable material and has a hinged connection with the buggy-body *b* at the rear of the seat, as is usual. The said buggy-boot is automatically locked when pressed down by my improved fastener, comprising a double-incline bar *c*, which is rigidly attached at 60 both ends to the rear end *d* of the buggy-body in a central position. The lower incline *e* of said bar is somewhat shorter or more abrupt and has more of an incline than the upper incline *e'*, so that the spring loop or catch *f* 65 will be held firmly by said part *e* after said spring has been pressed to a position to engage therewith. The spring loop or catch *f* is secured to the inner side of the buggy-boot above the incline-bar and in line therewith, 70 so that when the said buggy-boot is pressed down the lower transverse part *g* of the spring-loop will come in contact with the upper incline and will be pressed inwardly as the pressure on the boot continues and until after 75 said spring has passed the nose *h* of the bar and engages with the lower part of the incline. The spring in this position has a close engagement and exerts a constant pressure against the incline-bar, so that the buggy- 80 boot is held firmly closed and is not permitted to rattle. The spring *f*, as is shown in the drawings, has inner and outer straight surfaces *g* and *g'*, one of which engages with the upper incline and the other with the lower 85 incline. The said spring may be constructed of wire with its two ends formed into helices or coils *f' f'* to give it the required tension. It may be attached to the buggy-boot in any suitable manner. In the drawings the ends 90 from which the coils are formed terminate in eyes or loops *i*, through which a screw passes and enters the boot. The spring *j*, as shown in Fig. 4, has an opening *j'* in it to permit the entry of the nose *h* of the incline-bar and to 95 provide the two straight engaging surfaces *g* and *g'*. There may be more or less structural variation in this spring without departing from the spirit of my invention; but whatever the variation may be the said spring 100 must be attached to the buggy-boot and the double-incline bar to the buggy-body. The

parts are not interchangeable, and it is essential that the double-incline bar have an immovable attachment with the buggy-body. Of course it will be understood that the length 5 of the spring must be such as will insure a firm engagement thereof with the lower incline *e* when the buggy-boot is pressed tight. The boot may be opened by the hand, the spring yielding readily to a reasonable amount of up 10 pressure on said boot. As shown in Fig. 5, the eyes or loops *i*, formed in the ends of the spring, rest one on the other and are inclosed on two sides by a cap *i'*, through which the screw passes and tightens against the boot. 15 This cap prevents the screw from spreading the eyes *i*, and also prevents the spring from turning on the screw.

In case the boot is simply hinged by tacking the cloth that covers the frame to the 20 seat-board two fasteners may be used, one on each side of the body, opposite each other.

Having fully described my invention, I claim—

1. In a buggy-boot fastener, the combination 25 with the body of a buggy, and a boot, of

a spring secured to said boot, and a double-incline bar immovably secured to the rear end of the buggy-body in a position for the free end of the spring to engage therewith when the boot is being closed, the lower incline of said bar engaging with the lower end of the spring and holding it firmly when the boot is closed, substantially as specified. 30

2. In a buggy-boot fastener, the combination with the body of a buggy, and a boot, of 35 a double-incline bar immovably secured to said body, a spring secured to the boot in line with said double-incline bar, the lower end of said spring having two engaging surfaces that engage alternately with the double-incline 40 bar, one when the spring is actuated and the other when the boot is closed, substantially as described.

In testimony that I claim the foregoing as my own I hereto affix my signature in presence of two witnesses.

DANIEL W. KNEISLY.
